UNITED STATES PATENT OFFICE.

BENJAMIN DAY CHAMBERLIN, OF CORNING, NEW YORK, ASSIGNOR TO EMPIRE
MACHINE COMPANY, OF PORTLAND, MAINE, A CORPORATION OF MAINE.

MOLD FOR GLASS-BLOWING MACHINES.

1,156,057.

Specification of Letters Patent.

Patented Oct. 12, 1915.

Original application filed January 13, 1911, Serial No. 602,532. Divided and this application filed September 15, 1911. Serial No. 649,557.

To all whom it may concern:

Be it known that I, BENJAMIN D. CHAMBERLIN, a citizen of the United States of America, and a resident of Corning, New York, have invented certain new and useful Improvements in Molds for Glass-Blowing Machines, of which the following is a specification.

My invention has for its object to provide such a construction of actuating mechanism for blowing molds as will insure accuracy and smoothness of their action, a minimum of power required to operate it and simplicity of construction, the operations which are performed in the embodiments here shown, being a closing and opening of the molds, a dropping of the mold to permit the cooling of the mold by a water bath and a restoration of the molds to normal position.

For this purpose it consists essentially of a horizontally journaled frame having a cross-head upon which the mold parts are pivoted, the frame carrying certain parts of the mold-actuating mechanisms, which parts are governed by other mold-actuating parts carried on a fixed part of the machine, the connection between the two series of actuating parts being such that the frame and parts mounted thereon may readily be removed from and replaced in any appropriate blowing machine, such for instance as that shown in my other application, Serial Number 602,532, filed Jan. 13, 1911, of which this is a division.

It further consists in the construction, arrangement and combination of the several parts of which it is composed as will be hereinafter more fully described and claimed.

Referring to the accompanying drawings in which corresponding parts are designated by corresponding marks of reference: Figure 1 is a side elevation of one side of a duplex machine embodying my invention. Fig. 2 is a view partly in front elevation and partly in section on line x^2-x^2 of Fig. 1. Fig. 3 is an enlarged plan view of the mold, its actuating mechanism and its support.

The main actuating wheel or disk 12 mounted in the frame forms a part of the blowing machine fully described in my aforesaid prior application and it therefore needs no further description here.

In the bearing 20^a projecting from one side of the main frame 1 in the bottom at the

front end thereof is journaled a tubular 55 shaft 20 having fast thereon a pinion 20^b meshing with a rack segment 21 carried on the depending arm of a bell crank 21^a journaled at 21^b to the side of the main frame, the upper end of the bell crank engaging in 60 a cam track 21^c (shown in dotted lines in Fig. 1) on the inner face of the disk 12. The outer end of the tubular shaft 20 terminates in a cross head 20^e on the forward end of which is pivoted, by a pivot pin 20^d 65 parallel with the axis of the mold cavity, the two halves 22, 23, of the separable mold. The cam track 21^c is of such shape that it will impart a proper motion to the bell crank 21^a to oscillate the tubular shaft 70 through a limited arc sufficient to lower the mold halves into the cooling tank 7 and then raise them. Within the tubular shaft 20 is mounted, for axial and rotary movement, a shaft 24, which extends outwardly beyond 75 the cross head 20^e and has mounted thereon collars 22^a and 23^a, the collar 22^a being fast upon the shaft 24, and the collar 23^a adapted to slide thereon. The collar 22^a has two diametrically opposite trunnions 22^m the 80 lower of which is journaled in a rearward extension 22^b of the same half 22, while the other receives the forwardly extending arm of a bell-crank 24^a journaled at 24^b in the rear end of the cross head 20^e, the opposite 85 arm of the bell crank being connected by the link 24^c with the opposite half 23 of the mold, the construction being such that as the collar 22^a is pressed inwardly the mold halves are closed, and that as it is moved outwardly they are opened.

To accomplish the inward movement of the collar 22^a is the function of the collar 23^a, which is loose on the shaft 24, a spring 25 being interposed between it and the collar 22^a to cushion the closing movement and to provide a certain resiliency. The collar 23^a has trunnions thereon which are mounted in the bifurcated end of the forwardly extending arms of a bell crank 26 pivoted at 26^a to a bracket 26^b projecting from the side of the main frame 1, the laterally extending arm of the bell crank being connected by a universal joint 27 with the depending arm of a second bell crank 28, pivoted at 28^a on the side of the main frame, the upper arm of the last named bell crank having thereon a roller 28^b held on a periphery of the disk 12.

- by a spring 28^c. A peripheral enlargement or cam 28^a is mounted upon the disk in such position that during the rotation of the disk 12 it will contact with the roller 28^b to actuate the bell cranks 28 and 26 to shove the collar 23^a inwardly on the shaft 24, and thus, through the interposition of the spring 25, close the mold halves. When the cam passes from out of contact with the roller, which occurs while the blow-pipe is still vertical, the spring 28^c will actuate the bell crank 28 thus moving the bell crank 26 to again move the collar 23^a outwardly. In this movement the collar will by contacting with the nut 23^b on the end of the shaft 24, cause an outward axial movement of the shaft, which was pressed inwardly upon the closing of the mold, restoring the mold parts to open normal position.
- 20 As shown in Fig. 2, I prefer to make the machine a duplex one, that is to say to provide separate mold mechanisms on each side of the main frame, as is fully described in my prior application.
- 25 Having thus described my invention what I claim is:—
1. In a mold opening and closing and lowering mechanism the combination with a shaft, of mold parts pivoted thereon for opening and closing movement, means for imparting angular movement to the said shaft to raise and lower the molds, a second shaft concentric to the first named shaft and capable of axial movement in respect thereto, connections between the last named shaft and the mold parts to open and close the same
  2. In a mold opening and closing and lowering mechanism the combination with a tubular shaft, mold parts mounted thereon for opening and closing movements, a second shaft slidably mounted within the tubular shaft, connections between the last named shaft and the mold parts for opening and closing the same, means for imparting angular movement to the tubular shaft and means comprising a lever pivoted independently of the tubular shaft and parts carried thereon for imparting axial movement to the last named shaft.
  3. In a mold-actuating mechanism, the combination with a tubular shaft, of mold parts mounted thereon for opening and closing movement, a second shaft slidably mounted within the tubular shaft, two collars upon the sliding shaft, one of which is rotatable thereon, connections between one of the said collars and the mold parts to open and close the same, a lever pivoted independently of the tubular shaft and connected with the other collar for reciprocating the sliding shaft and the other collar, a spring interposed between the collars, and means for rotating the tubular shaft.

BENJAMIN DAY CHAMBERLIN.
